(57) **CLAIM**

The ornamental design for a mobile platform for contactless load inspection, especially for containers on transportation means, as shown and described.

DESCRIPTION

FIG. 1 is a top, front, and left side perspective view of the mobile platform for contactless load inspection, especially for containers on transportation means, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a front view thereof.
